MANDREL FOR PNEUMATIC-TIRE TUBES.

1,316,275.

Specification of Letters Patent. Patented Sept. 16, 1919.

Application filed March 7, 1919. Serial No. 281,282.

To all whom it may concern:

Be it known that we, DON A. CLARK and CLYDE E. LOWE, citizens of the United States, residing at Cleveland, in the county of Cuyahoga and State of Ohio, have invented a certain new and useful Improvement in Mandrels for Pneumatic-Tire Tubes, of which the following is a full, clear, and exact description, reference being had to the accompanying drawings.

This invention relates to mandrels for pneumatic tubes and has for its special object the provision of a bridge for joining together the ends of such a mandrel whereby its use is facilitated. The body of the mandrel is preferably but not necessarily of sheet metal and is made of substantially torus form but with its ends spaced apart so that the rubber tube can be removed therefrom after curing. Our improved bridge comprises a removable section adapted to connect these ends and form a support for the whole during the curing.

In the drawings accompanying and forming a part of this application we have shown certain mechanical constructions in which our inventive idea can be embodied, although it will be understood that said drawings are illustrative only and do not limit us to the particular features therein shown. In the drawings, Figure 1 is a detail view partly in section of a portion of a mandrel embodying our invention together with a tube thereon and part of the winding used during the curing; Fig. 2 represents a side elevation of our improved bridging member; Fig. 3 is a sectional view of the bridging-member closed; and Fig. 4 of the same member open; Fig. 5 is a plan view of a complete mandrel showing our bridge in place prior to the application of the tube and its winding; Fig. 6 illustrates one half of the bridge; Fig. 7 is a sectional view showing a modified device for holding the bridge sections together.

Describing by reference characters the parts shown in these drawings, 1 represents the mandrel, which, as above described, is comprised preferably of sheet metal and is preferably (but not necessarily) substantially circular both in general plan and in particular cross section; in other words of torus shape. This mandrel is discontinuous at one point as shown at 2—2 the ends being preferably square and facing each other;

and to bridge over this gap and connect it we have provided a device consisting of a pair of similar sheet metal channels 3—3, each semi-circular in cross section at every point but curved as a whole from end to end upon a radius equal to that of the mandrel itself. These channels are fastened together at their point of greatest diameter by suitable means such as the hinge 4, whose axis is tangent to the body at its largest point. Suitable means are provided for holding the halves together, such means preferably consisting of one or more spiral springs 5 which traverse the body and are connected at their ends to the channel members, but other means such as the snap 6 shown in Fig. 7 can be employed. In Figs. 2—6 inclusive we have shown the inner edges of the channel as formed with notches 7 for the insertion of the fingers whereby the device may be opened and applied to or removed from the mandrel. The internal diameter of the bridge is preferably such as snugly to receive the adjacent mandrel ends as shown in Fig. 1 although no damage is done if the same be slightly undersized as it will then be clamped the more tightly. The length of the bridge is also such to slightly overlap the ends of the mandrel.

In use, after the bridge has been applied as described, the remainder of the mandrel is covered with a raw rubber gum mixed with the vulcanizing material, as shown at 10 in Fig. 1, and the same terminating just short of the bridge. The entire device, bridge and all, is then wrapped spirally by strips of textile fabric as shown at 11, said fabric being preferably wet or moist when applied. This wrapping is generally done by machinery and is continuous over the bridge as well as over the rubber part, the thickness of the bridge being substantially the same as that of the rubber so that the complete and uniform wrappings can easily be effected by machinery. The mandrel with its covering is then transferred to the curing oven where it is hung up, preferably by the bridge, so that the supporting device will have no injurious effect upon the rubber tube. The heat of the oven serves to dry the fabric and thereby places a powerful pressure upon the rubber and also cures the rubber under that pressure whereby an excellent cure is made.

As already pointed out our improved

bridge can be employed with cast iron mandrels equally well as those of sheet metal, but sheet metal mandrels are preferable in that they are lighter to handle and lead to 5 a more satisfactory cure of the rubber because of their smaller heat capacity. It will be understood that many changes can be made without departing from our invention.

Having thus described our invention, 10 what we claim is:—

1. A mandrel for pneumatic tire tubes comprising a curvilinear body having its ends arranged opposite and in alignment with each other and spaced apart, in combination 15 with a hollow arcuate sheet metal body of length greater than the distance between said ends and adapted to receive the same, said body being made of relatively movable sections whereby it can be applied 20 and removed.

2. A mandrel for pneumatic tire tubes comprising a curvilinear body having its ends arranged opposite each other and spaced apart, in combination with a hollow 25 arcuate sheet metal body of length greater than the distance between said ends and adapted to receive the same, said body consisting of a plurality of channel members hinged together upon a longitudinal axis.

3. A mandrel for pneumatic tire tubes comprising a curvilinear body having its ends arranged substantially opposite and spaced from each other and spaced apart, in combination with a hollow arcuate sheet 30

metal body of length greater than the distance between said ends and adapted to receive the same, said body being split longitudinally into separable sections, and means for securing said sections detachably together. 35

4. A torus shaped discontinuous tube mandrel having its ends spaced apart in combination with an arcuate sectional sheet metal bridge adapted to overlap and join together the ends of said mandrel. 40

5. A bridge for tube mandrels consisting of an arcuate hollow sheet metal body split longitudinally into two sections which are hinged together upon an axis tangent to said body at its point of greatest radius. 50

6. A bridge for tube mandrels consisting of an arcuate sheet metal body split longitudinally into two parts, and a transverse tension spring connecting said parts.

7. A bridge for tube mandrels consisting of an arcuate sheet metal body split longitudinally into two parts, hinge means connecting said parts, and a tension spring attached to each of said parts and tending to hold them together. 55

8. A bridge for tube mandrels consisting of an arcuate hollow sheet metal body split longitudinally into sections, and means for holding said sections detachably together.

In testimony whereof, we hereunto affix 60 our signatures.

DON A. CLARK.
CLYDE E. LOWE.
